WEATHER VANE

Stephen Kwolek, 8385 Woodcrest Drive,
Westland, Mich. 48185

Filed June 18, 1970, Ser. No. 23,561

Term of patent 14 years

Int. Cl. D10—07

U.S. Cl. D52—6

FIG. 1

FIG. 2

FIG. 3

FIG. 1 is a front elevational view of a weather vane showing my new design;

FIG. 2 is a side elevational view thereof; and

FIG. 3 is a top plan view thereof.

I claim:

The ornamental design for a weather vane, as shown.
